UNITED STATES PATENT OFFICE.

PETER GRASSMANN AND MARCELLUS B. CHEEK, OF AURORA, INDIANA.

FEED-WATER HEATER.

SPECIFICATION forming part of Letters Patent No. 368,147, dated August 9, 1887.

Application filed February 14, 1887. Serial No. 227,600. (No model.)

To all whom it may concern:

Be it known that we, PETER GRASSMANN and MARCELLUS B. CHEEK, both of Aurora, Dearborn county, Indiana, have jointly invented a new and useful Improvement in Feed-Water Heaters, of which the following is a specification.

Our invention is more particularly designed for use in those steam-generators which comprise two or more horizontal boilers, and is here illustrated in connection with a pair of such boilers.

The leading feature of our invention relates to an arrangement of feed-water pipes which utilizes them to uphold the furnace-crown. Our feed-water pipes being U-shaped and extending along over the space between the boilers are (in the preferred form of our invention) themselves suspended by suitable rods from bridges which rest upon the boilers and span the space between them. Each suspension-rod is preferably so incased in a tube communicating with and resting upon the contiguous feed-water pipe as to protect it from direct contact with the furnace heat.

The invention consists, further, in connecting the said feed-water-heating pipes with a special steam-dome whose communication with the steam-chest of the steam-pump enables it to be started and the consequent supply of water to the boilers to be initiated considerably in advance of any output of steam from the boilers themselves.

The above and sundry subsidiary features of our invention are fully set forth in our specification and claims.

In the accompanying drawings, Figure 1 is a perspective rear view of an arrangement of feed-water pipes and associated devices embodying our invention. Fig. 2 is a transverse section at or near the rear end of the boilers, looking forward. Fig. 2^a is an enlarged detailed sectional view. Figs. 3 and 4 are sections which respectively represent two different modifications of the mode of supporting our feed-water pipes from the bridges. Figs. 5 and 6 are respectively a transverse section and a top view of a modification of our tile-support.

The grate, the fire-walls, and other details of the furnace are omitted from the above figures.

The following parts may be of customary construction, and consequently require no specific description.

1' may represent two common horizontal steam-boilers. 2 may represent a customary mud-drum, which may receive the delivery end of the feed-water pipe 3 in the accustomed way. 4 and 5 may respectively indicate the ordinary steam-chamber and steam-service pipe leading to the main engine.

Associated with the above familiar parts of a steam-generator is our arrangement of feed-water apparatus, now to be described.

6 represents the pipe which conveys cold water from the steam-pump.

7 is an air-collector. From the base of the air-collector 7 a branch, 8, leads to an ascending pipe, 9, whose only ordinary communication with descending pipe 10 is through the U-shaped coil 11, located in the upper part of the furnace-space 12, between and parallel to the boilers 1'. A branch, 13, connects the lower part of the descending pipe 10 with pipe 3, which delivers the feed-water to the mud-drum.

In the preferred form of our invention the pipes 9 and 10 communicate at their upper ends with each other and with an auxiliary steam-dome, 14, whose pipe 15 leads to the steam-chest of the steam-pump. (Not here shown.)

16, 17 represent two stop cocks, of which one, 16, is in the ascending pipe 9, and the other, 17, is in the descending pipe 10.

In the starting of the apparatus the cock 16 is tightly shut and the cock 17 opened. The effects of such an arrangement of the cocks are, first, to permit the steam generated in the coil 11 to escape to the pump, and by so doing to start the feed-water in motion, and, secondly, to compel the feed-water to traverse the coil 11, so as to get preheated on its route to the mud-drum.

Should it be desired, after commencement of active generation in the main boilers, to draw steam for the pump wholly from them in the usual way, communication is opened with the main steam-pipe 5, and the passage to the auxiliary steam-chamber is closed, either by closure of the cock 17 or of the throttle 18. Lastly, by closure of throttle 18 and a greater or less opening of the cocks 16, 17 feed-water

may be delivered in greater volume and at any desired reduction of temperature.

The rear extremities of our U-formed coil 11 are supported by their junction with the stand-pipes 9 10, and elsewhere the said coil is supported by the following means:

We provide one or more bridges, 19, of cast-iron, from which depend rods or bolts 20, whose heads 21, being engaged in said pipes, and whose screw-threaded upper ends being secured in nuts 22, that rest upon the bridge-crowns, the said coil becomes thereby firmly suspended from said bridges. To protect the said rods or suspenders from the direct contact of the heated gases of the furnace they are inclosed in the tubes 23, which are kept filled with water by their communication with the said feed-water pipes, as shown at Fig. 2^a of the drawings. We utilize the thus upheld feed-water coil 11 to support in whole or in part the tile crown or coping of that portion of the furnace-space which intervenes between the boilers.

Various modifications may obviously be made of the above-described form of our invention without departing from the essential features thereof. For example, contact of the suspending-rods with the furnace heat may be avoided without immersion of the rods in the water-space, as shown in Fig. 6, or the suspenders may be of tubular form and screw-threaded at their upper portions for the fastening-nuts, as shown in Figs. 3, 4, and 5. The feed-water coil may be composed of more than two convolutions, as represented in Figs. 3 and 4.

Our generator may be provided with cus-

tomary or any suitable check-valves, 25, stop-cocks 26, and mud or blow-off cocks 27.

We claim as new and of our invention—

1. The combination, with a pair of steam-boilers, of the tile furnace-crown 24, resting on a feed-water coil, 11, which is supported by suspension-rods 20 from one or more bridges, 19, whose ends rest upon the boilers, substantially as set forth. 40

2. In a feed-water heater, the combination, with the heating-coil and suspenders for suspending said coil, of a water-jacket surrounding said suspenders and having communication with the feed-water, substantially as set forth. 50

3. The combination, with the heating-coil 11 and the bridge 19, of the bolt 20, for suspending said coil from the bridge, and the pipe 23, incasing said bolt and having direct communication with the interior of said coil, substantially as and for the purpose set forth. 55

4. The combination, with a preheating feed-water coil, 11, of the auxiliary steam-passage for conveying steam to the steam-chest of the pump, substantially as described. 60

5. The combination, with the feed-water heater 11 and the system of feed-water and auxiliary steam-passages 9 10 14 15, of the stop-cocks 16 17, all arranged as shown. 65

In testimony of which invention we hereunto set our hands.

PETER GRASSMANN.
MARCELLUS B. CHEEK.
